(57) **CLAIM**

The ornamental design for the bow string vibration suppressor, as shown and described.

DESCRIPTION

FIG. 1 is a perspective view of the bow spring vibration suppressor attached to a bow;

FIG. 2 is a perspective view illustrating the bow string vibration suppressor of the present invention in an extended condition;

FIG. 3 is a perspective view of the bow string vibration suppressor of the present invention in a retracted condition;

FIG. 4 is a front elevation view thereof;

FIG. 5 is a rear elevation view thereof;

FIG. 6 is a left elevation view thereof;

FIG. 7 is a right elevation view thereof;

FIG. 8 is a top plan view thereof; and,

FIG. 9 is a bottom plan view thereof.

The broken lines, including bow in FIG. 1, and threaded fastener illustrated in FIGS. 2-9, form no part of my claimed design.
